UNITED STATES PATENT OFFICE.

FRANK WESTCOTT, OF SENECA FALLS, NEW YORK.

DESIGN FOR A TABLE-MAT.

SPECIFICATION forming part of Design No. 13,002, dated June 20, 1882.

Application filed May 6, 1882. Term of patent 7 years.

To all whom it may concern:

Be it known that I, FRANK WESTCOTT, of Seneca Falls, in the county of Seneca and State of New York, have invented a new and valuable Design for Table and other Mats; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a plan view of my mat. Fig. 2 is a perspective section.

This design has relation to folding table-mats; and it consists in the ornamental scroll-work printed on the alternate light strips, these being separated and relieved by dark strips on each side of each light strip, as hereinafter set forth.

In the accompanying drawings, the letter *a* designates the alternate light strips, each of which is ornamented by printing thereon an

elongated ornamental scroll-work consisting of a central shell-like figure, *a*, from which extend toward each end of the strip scroll-form branches *b*.

On each side of each ornamented light strip *a* is arranged a dark strip, *c*, which serves to separate the light strips and relieve the configuration thereon, forming a background and bringing out the effect of the printed figures in a neat and tasteful manner.

What I claim and desire to secure is—

The design for folding table-mats, consisting in the ornamental scroll-work printed on the light strips, separated and relieved by the dark strips on each side of each light strip, as shown and set forth.

In testimony that I claim the above I have hereunto subscribed my name in the presence of two witnesses.

FRANK WESTCOTT.
